UNITED STATES PATENT OFFICE.

WILLIAM A. BREWER, OF PITTSBURGH, PENNSYLVANIA, ASSIGNOR, BY MESNE ASSIGNMENTS, TO P. H. MURPHY COMPANY, OF PARNASSUS, PENNSYLVANIA, A CORPORATION OF PENNSYLVANIA.

CAR-ROOF.

1,130,370.

Specification of Letters Patent.

Patented Mar. 2, 1915.

Application filed May 5, 1913. Serial No. 765,510.

To all whom it may concern:

Be it known that I, WILLIAM A. BREWER, a citizen of the United States, and a resident of the city of Pittsburgh, in the county 5 of Allegheny and State of Pennsylvania, have invented a new and useful Improvement in Car-Roofs, of which the following is a specification.

This invention relates to car roofs, and 10 more particularly to outside metal roofs comprising movably mounted transversely extending sheets whose side marginal portions are connected by flexible or loose waterproof seams.

15 It has for its principal objects to provide improved means for securing the end sheets so that the sheets are retained throughout their length; to allow for a limited movement of the end sheets and yet prevent leakage under them; and to attain certain advantages which will hereinafter more fully appear.

20 The invention consists in securing the end sheets continuously along the end of the car; 25 and it further consists in the parts and in the arrangements and combinations of parts hereinafter described and claimed.

25 In the accompanying drawing, which forms part of this specification, and wherein like symbols refer to like parts wherever they occur, Figure 1 is a top plan view of the end portion of a car roof illustrating an embodiment of the invention; Fig. 2 is an end elevation; Fig. 3 is a vertical section on 30 the line 3—3 of Fig. 2 on an enlarged scale; Fig. 4 is a vertical section on the line 4—4 of Fig. 2; and Fig. 5 is a vertical section on the line 5—5 of Fig. 2.

35 The roof shown in the drawing is of the "radial" type. That is, the roof is arched or curved on a radius. The metal sheets 1, of which only an end sheet is shown, extend continuously across the car from eaves to eaves. The ends of the sheets may be 40 turned down over the eaves, or they may be otherwise suitably arranged and secured in any desired manner. The outer side marginal portion of the end sheet is turned down over the end of the car, as at 2, into a 45 continuous recess or rabbet 3 in the end fascia or molding 4.

50 The roof substructure shown in the drawing is of the type known as the "all metal"

type. That is, the purlins and carlines or the longitudinal and transverse frame members are of metal. In the drawing, only the purlins 5 are shown. These purlins are supported at their ends on the end plate 6; the ends of the purlins being turned down over the outside of the end plate and secured thereto by bolts 7.

55 An elongated retaining cap 8 of angle section, and preferably made of sheet metal, is secured to the end fascia 4, below the rabbet 3, at intervals throughout its length by 60 bolts 9 which extend entirely through the end plate 6. The cap is also secured at points between the bolts 9 by nails 10 which are preferably driven into the end plate. Preferably, the cap 8 is made in one piece 65 and extends from side to side of the car, but in some cases, if desirable, the cap may be made in two or more sections whose meeting ends may be made to abut or overlap. The margin of the portion 8^a of the end cap, 70 which overlaps the roof sheet, is preferably bent back or hemmed, as at 8^b, so as to reinforce and stiffen the end cap along the overlapping edge.

75 In practice, the overlapping portion 8^a of the cap is made to lie close to the roof sheet so as to prevent the sheet from lifting, but with sufficient looseness to permit the sheet to move lengthwise and sidewise; and in order to prevent an accumulation of cinders or any other substance that might be forced 85 between the cap and roof sheet into the rabbeted portion 3 of the fascia 4, and also to provide the proper drainage for any water which may get under the cap, the downturned portion of the cap is corrugated or crimped vertically at intervals throughout the length of the cap, as at 11. Preferably, these corrugations are flared or widened 90 toward the bottom edge of the downturned portion of the cap to further prevent clogging. These corrugations 11 also serve to 95 stiffen the cap. The retaining cap, in addition to holding down the roof sheet, also serves as a tie-plate and stiffening element 100 for the end of the car in the region of the roof, particularly in cases where the cap extends continuously from side to side of the car.

105 Obviously, the structure admits of considerable modification without departing

from the invention. Therefore, I do not wish to be limited to the specific construction and arrangement shown.

What I claim is:

- 5 1. A flashing strip and retaining member for the end of a curved car roof and having a horizontally disposed flange portion and a vertical flange portion, the vertical portion of said strip being corrugated vertically, whereby it is vertically flexible.
- 10 2. In a curved car roof, the combination with an end sheet, of an upwardly curved flexible flashing strip and retaining member conformable to the curve of the roof, said
- 15 3. flashing strip consisting of a vertical flange portion fastened to the end of the car below the eaves and a horizontal flange portion overlapping the adjacent marginal portion of the end sheet, the vertical flange portion of said flashing and retaining member being corrugated vertically, the corrugations being widened toward the bottom edge of the flange portion, whereby said flashing and retaining member is flexible in a vertical plane and substances may readily escape from under it.
- 20 4. In a car roof, the combination with an end sheet, the marginal portion of said end sheet, being turned down over the end of the car, of an end flashing strip and retaining member comprising an angle shape sheet metal cap having one flange corrugated vertically and fastened to the end of the car between the corrugations and having the
- 25 5. other flange smooth and overhanging said end sheet, whereby said end sheet is retained at the end of the car, said corrugations stiffening said flange to retain said end sheet and making said cap flexible between its ends.
- 30 6. In a car roof, the combination with an end sheet, the marginal portion of said end sheet being turned down over the end of the car, of an end flashing strip and retaining member comprising an angle shape sheet metal cap having one flange turned down and fastened to the end of the car and having its other flange horizontally disposed

over the end sheet, whereby said end sheet is movably secured at the end of the car, the downturned flange of said cap being corrugated vertically, the corrugations being widened toward the bottom edge of said downturned portion, whereby said cap can be bent on its longitudinal axis in a vertical direction.

5. In a curved arched car roof, the combination with an end sheet extending continuously across the car from eaves to eaves, of a continuous angle shape retaining member one of whose flanges is secured along the end of the car, the other flange being disposed inwardly so as to overhang the end sheet, said retaining member being corrugated transversely whereby it is flexible to conform to the curvature of the roof.

6. In a curved arched car roof, the combination with an end sheet extending continuously across the car from eaves to eaves, the end of the car having a continuous rabbet into which the side marginal portion is turned down, of a continuous angle shape retaining member one of whose flanges is secured along the end of the car below said rabbet, the other flange being disposed inwardly so as to overhang the end sheet, said first mentioned flange being provided with vertical corrugations spaced from the end of the car whereby said retaining member is flexible to conform to the curvature of the roof and substances can escape from under it.

7. An angle shape retaining strip for the eaves end of a curved car roof, said strip comprising a vertical flange having tapering vertical corrugations increasing in size toward the bottom whereby said flange is vertically flexible and the escape of cinders from thereunder is facilitated.

Signed at Pittsburgh, Pennsylvania, this 28 day of April 1913.

WILLIAM A. BREWER.
